US0D1059001S

(12) **United States Design Patent** (10) **Patent No.:** **US D1,059,001 S**
(45) **Date of Patent:** **** Jan. 28, 2025**

(54) **SHOE**

(71) Applicant: **ROTHY'S, INC.**, San Francisco, CA
(US)

(72) Inventors: **Stephen P. Hawthornthwaite**, San
Francisco, CA (US); **W. Roth Martin**,
San Francisco, CA (US)

(73) Assignee: **ROTHY'S, INC.**, San Francisco, CA
(US)

(**) Term: **15 Years**

(21) Appl. No.: **29/735,070**

(22) Filed: **May 18, 2020**

Related U.S. Application Data

(62) Division of application No. 29/641,383, filed on Mar.
21, 2018, now Pat. No. Des. 884,317.

(57) **CLAIM**

The ornamental design for a shoe, as shown and described.

DESCRIPTION

FIG. 1 is front left perspective view of a shoe showing our new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines shown in the figures are included for the purpose of illustrating environmental structure of the shoe and form no part of the claimed design.

1 Claim, 7 Drawing Sheets
